UNITED STATES PATENT OFFICE.

WILLIAM H. JOHNSON, OF DELANCY, ASSIGNOR OF ONE-HALF TO GEORGE E. MARVINE, OF DELHI, NEW YORK.

HAME-FASTENER.

SPECIFICATION forming part of Letters Patent No. 293,655, dated February 19, 1884.

Application filed January 30, 1883. (No model.)

To all whom it may concern:

Be it known that I, WILLIAM H. JOHNSON, a citizen of the United States, residing at De Lancy, in the county of Delaware and State 5 of New York, have invented certain new and useful Improvements in Hame-Fasteners; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 Figure 1 is a view of the under side of one of the parts of the fastener. Fig. 2 is a view of the under side of the other part of the fastener. Fig. 3 is a side view of both parts in position, ready to fasten the hames. Fig. 4 20 is a side view of the parts in position after the fastening is completed.

Like letters designate corresponding parts in all of the figures.

This fastening is composed of two parts—the 25 hook part A and the eye or catch part B. The hook part A has a strap, C, of leather or other flexible material, attached to it near its free end. Both parts may be made either of wrought iron or malleable iron or other suitable metal. The hook part A has a set of 30 hook projections or teeth, *a a*, arranged in a row on its under, preferably somewhat rounded, side. The catch part B has a long slot, *b*, in it of sufficient length to embrace all the 35 projections *a a* of the other part, and it has a cross-bar or catch, *c*, at its free end, to catch over any one of the said projections. Two of such bars, at sufficient distance apart to admit one projection *a* between them, may be 40 used, so as to catch over two projections at once, and thus add to the strength of the fastener. The catch part also has a loop, *d*, projecting from its under side, to receive and retain the free end of the strap C after the 45 fastening is completed. Both parts are permanently attached by bends or hooks *e f* respectively taking into and holding by the respective loops or eyes *g h* of the hames D E.

The method of fastening by means of this fastener is as follows: The strap C of the hook-fastener A is first passed through the loop or eye *h* of the other hame, E, around the hook *f* of the other part, B, and the parts are brought into position, as shown in Fig. 3. The strap C is then drawn upon to draw the ends of the 55 hames toward each other till they tightly embrace the collar. The bar *c* of the catch part B is then caught over the nearest projection *a* of the hook part A, and the fastening is completed. The free end of the strap C is then 60 passed through the loop *d*, as shown in Fig. 4.

Not only is this fastening simple, strong, and secure, but it is very convenient and easy to manipulate, the tightening by means of the strap C being similar in operation to that of 65 fastening by an ordinary buckle-strap. Also, the strap being flexible, there is greater power to draw tightly thereon. Besides, the strap, by passing around the end of the part B, tends to press it against the teeth of the part A, and thereby facilitates the locking of the fastener. This fastener is more easily adjusted to the 70 shape of the collar than fasteners made of rigid levers or eccentrics.

It is obvious that the strap C might be attached to the catch part B instead of the hook part A, but not to so good advantage.

What I claim as my invention is—

In a hame-fastener, the combination of the part A, provided with hooks *a a*, and adapted 80 to be attached to the eye *g* of one hame, D, the part B having a long slot, *b*, therein, and provided with a catch, *c*, and adapted to be attached to the eye *h* of the other hame, E, and the flexible strap C, secured to the free 85 end of the hook part A, and adapted to be passed through the hame-eye *h*, around the part B, all substantially as and for the purpose herein specified.

In testimony whereof I affix my signature 90 in presence of two witnesses.

WILLIAM H. JOHNSON.
